UNITED STATES PATENT OFFICE.

JOSIAH C. DUNKELBARGER, OF CHENEYVILLE, ILLINOIS.

POWER MECHANISM.

No. 821,226.

Specification of Letters Patent.

Patented May 22, 1906.

Application filed July 18, 1905. Serial No. 270,257.

To all whom it may concern:

Be it known that I, JOSIAH C. DUNKELBARGER, a citizen of the United States, residing at Cheneyville, in the county of Ver-
5 milion, State of Illinois, have invented cer-
tain new and useful Improvements in Power
Mechanisms; and I do hereby declare the fol-
lowing to be a full, clear, and exact descrip-
tion of the invention, such as will enable
10 others skilled in the art to which it apper-
tains to make and use the same.

This invention relates to power mech-
anisms, and more particularly to pedal-operat-
ing mechanisms, and has for its object to
15 provide a mechanism of this kind which will
be simple in arrangement and which may be
manufactured at a low figure.

Other objects and advantages will be ap-
parent from the following specification, which
20 describes an embodiment of the present in-
vention.

In the drawings forming a portion of this
specification, and in which like numerals of
reference indicate similar parts in the sev-
25 eral views, Figure 1 is a side elevation of the
present invention. Fig. 2 is a front view.
Fig. 3 is a top plan view. Fig. 4 is a detail
perspective view of one of the clutch mech-
anisms. Fig. 5 is a transverse section through
30 the clutch mechanism on line 5 of Fig. 4.

Referring now to the drawings, the pres-
ent invention comprises a frame consisting of
horizontal sills 5, connected at their forward
ends by means of a cross-bar 6 and having
35 uprights 7 hinged to their rearward ends for
movement longitudinally of the sills. Brace-
rods 9 are pivoted at their rearward ends to
the upper ends of the uprights 7 and have
perforations 9' therein adjacent to their for-
40 ward ends, arranged in longitudinal series
and adapted for interchangeable registration
with similar perforations 10', formed in up-
wardly and forwardly slanted members 11,
which are secured to the sills 5, it being thus
45 seen that the braces 9 are adjustable to hold
the uprights 7 at different angles to the sills
5, confining-pins 12 being engaged in the reg-
istering perforations 9' and 10'.

Bearings 13 are formed in the uprights 7,
50 and journaled in these bearings there is a

transversely-extending horizontal shaft 14,
which is squared between its ends and upon
which is mounted for rotation therewith a
larger sprocket-wheel 15 and a smaller
sprocket-wheel 16, the two being secured to-
gether and being slideable longitudinally of
the shaft. Outwardly of the uprights 7
ratchet-wheels 17 are mounted upon the
shaft 14, and these ratchet-wheels have
drums 18 at either side of their ratchet-teeth 19,
the drums being of lesser diameter than
the outer periphery of the teeth.

Bands 20 and 21 are engaged with the
drums 17 and 18, as shown, there being two
pairs of these drums, one pair for each ratchet-
wheel. The ends of the bands of each pair
are secured to levers 22, which extend for-
wardly, as shown. Pivoted between the
bands are dogs 23, arranged to engage the
ratchet-teeth 19 when moved forwardly and
70 to slip thereover when moved rearwardly.

Forwardly-converging rods 24 are secured
to the upper ends of the uprights 7 and have
a forwardly-extending rod 25 secured to
their forward ends, this rod 25 having a 75
transverse arm 26 at its forward end pro-
vided with pulleys 27 at its ends. A cable is
engaged with these pulleys and has its ends
secured to the levers 22, the arrangement be-
ing such that when one of these levers is 80
moved downwardly the other one will be
moved upwardly. Adjacent to their for-
ward ends the levers 22 are provided with
foot-plates 29, and it will be seen that the le-
vers may be moved to revolve the shaft 14. 85

A chain 30 is engaged with the sprocket-
wheel 15 and may be shifted from one to the
other of these connected sprocket-wheels 15
and 16, as desired, to produce different re-
sults, the chain being engaged with an op- 90
erative mechanism also, as will be readily un-
derstood.

It will be seen that movement of the up-
rights 7, as mentioned above, will move the
shaft 14 and the sprocket-wheels carried 95
thereby to vary the tension of the chain.

What is claimed is—

A mechanism of the class described com-
prising a frame, a shaft journaled in the up-
rights, ratchet-wheels carried by the shaft, 100

drums carried by the ratchet-wheels, bands engaged with the drums, levers secured to the bands, dogs pivoted to the bands and adapted for engagement of the ratchet-teeth 5 for movement of the shaft therewith in one direction, connections between the levers, said connections being arranged to move one of the levers in one direction when the other le-

ver is moved in the opposite direction and a sprocket-wheel mounted upon the shaft.

In testimony whereof I affix my signature in presence of two witnesses.

JOSIAH C. DUNKELBARGER
